UNITED STATES PATENT OFFICE.

CARL ANTON MÜLLER AND FRANZ ANGER, OF TEPLITZ, AUSTRIA-HUNGARY, AS
SIGNORS TO THE FIRM OF SCHUBERT & SALZER MASCHINENFABRIK A. G., OF CHEM-
NITZ, GERMANY.

MACHINE FOR MAKING FRINGES.

1,006,776.

Specification of Letters Patent. Patented Oct. 24, 1911.

Application filed November 12, 1909. Serial No. 527,715.

To all whom it may concern:

Be it known that we, CARL ANTON MÜLLER and FRANZ ANGER, subjects of the Emperor of Austria-Hungary, and residing at 5 Teplitz, Bohemia, Austria-Hungary, have invented certain new and useful Improvements in Machines for Making Fringes, of which the following is a specification.

The present invention has reference to a 10 new or improved machine for producing fringes on shawls, wraps, scarfs, carpets, table and bed covers, and the like, which process is now carried out so that the fringe is made up of a plurality of loops, which 15 are formed one after the other from a single length of thread. Our new process greatly improves on this obviously slow and laborious procedure, inasmuch as here all of the fringe loops are attached to the work 20 piece in a single operation, enabling the operator to easily turn out ten times as much work as with the old process, thereby greatly reducing the cost of production.

Since in the old process, the running-in 25 of the loops into the cloth is done by hand, the work turned out must needs be of a more or less irregular appearance, one loop for instance being run-in farther or more obliquely than the succeeding one, and above 30 all the interspaces between the several tufts will always be unequal. According to our invention the loops or tufts are run-in and spaced apart absolutely evenly with great benefit to the appearance of the finished 35 article.

The principle of the invention consists in the employment of a plurality of rigidly held needles, having the eye at the upper, pointed end, and in the operation of placing 40 the workpiece unto these needles and then withdrawing it again, whereby at all needles simultaneously the loops for the tufts are formed, which are then knotted or otherwise dressed in the usual manner.

In order to make the invention more readily understood, we will now describe it with reference to the accompanying drawing, in which—

Figure 1 represents a front view of the 50 machine, Fig. 2 a cross-section thereof, Fig. 3 shows an auxiliary tool, and Figs. 4, 5, 6 and 7 represent various stages of the looping operation, the essential parts only being shown, partly in section.

To the machine frame *a*, in the shape of 55 a table, is secured at the forward end a plate *b* in which are suitably secured the needles *c*, curved inwardly at their upper end and having the eye just below the point. We will hereinafter refer to this needle 60 studded plate as "comb."

Over the main plate of the machine travels a beam *f*, adjustably secured thereto by means of the wing-nut *s* and screw bolt *e*, the latter extending through the slot *d* in 65 the table *a*. A bar *h*, hinged at *g*, to the beam *f*, contacts with the latter over its entire length, forming a clamp, and it can be locked in the closed position by the locking device *i*. At the rear of the beam *f* there 70 are provided eyes, which may be closed all around as at *l*, Fig. 2, or open below, as at *k*, Fig. 4.

Below the described parts are provided a number of cross-bars *m*, which carry as 75 many bobbins *n* as there are needles. Into each needle is inserted the thread *o*. This thread, as will presently be described, is quadrupled during the operation, a great improvement over the old practice, where 80 always two threads are drawn through each needle in order to turn out a tuft of four strands. All the loose thread ends are then clamped between the members *f* and *h*, as shown in Fig. 4. The work piece *p* is now 85 placed upon the row of needles (Fig. 5) when above the cloth there are formed the loops, which owing to the inward curvature of the needles, present a bulge or eye *q*.

The auxiliary tool, a handled and pointed 90 rod *r*, is now longitudinally inserted through all of these eyes *q* and is then moved over to the beam *f*, where it is secured in the stationary eyes *k*, *l* (Fig. 6), the thread uncoiling from the spools. The distance between comb and beam *f* determines the 95 length of the fringe tufts. Upon the cloth now being lifted off the needles, the threads *o* are correspondingly drawn out (Fig. 7) and there is now formed a tuft of four 100 threads each at each needle, which threads are then cut just above the member *h*. The rod *r* is withdrawn, the clamp *f*, *h* is opened, and new threads are clamped in by simply drawing out the thread ends depending from 105 the needles, thus doing away with fresh threading after each cutting of the loops. The machine, therefore, allows of continuous

operation, without necessitating previous cutting to size of the threads.

What we claim as new and desire to secure by Letters Patent is:—

- 5 1. In a machine for making fringes, a frame; a plurality of needles secured thereon, points upward and each needle having the eye just below the point; thread clamping means adjustable toward and from said needles; an auxiliary thread holding tool; and means for temporarily securing said tool to said clamping means, substantially as and for the purpose set forth.
- 10 2. In a machine for making fringes, a frame; a comb secured thereon, comprising a plate and a plurality of needles secured therein each needle being curved at the upper pointed end and having the eye just

below the point; a clamping device for securing the free ends of the threads; means for adjusting said clamping device relative to said comb and for securing it in the desired position, and additional thread holding means for temporarily anchoring the thread loops to said clamping device, the parts being constructed, arranged and co-operating substantially as and for the purpose set forth. 20 25

In testimony whereof we affix our signatures in presence of two witnesses.

CARL ANTON MÜLLER.
FRANZ ANGER.
